UNITED STATES PATENT OFFICE

2,529,839

AIR CONDITIONER

Thomas H. Garvey, Natick, and Paul V. Scally,
Randolph, Mass.

Application June 10, 1947, Serial No. 753,606

3 Claims. (Cl. 261—106)

1

This invention pertains to air conditioners and more particularly to a device to wash, humidify or dehumidify air which is circulated therethrough.

One object of this invention is to provide a novel and efficient air conditioning unit. A further object is to provide such a unit which will efficiently wash or clean the air and which may be accurately controlled to circulate the required amount of moisture at the desired temperature for contact with the air, thereby to control its moisture content. A further object is to provide such a unit which may be easily cleaned and which may be readily installed in common air circulating systems.

Other and further objects and advantages of the invention will be pointed out in the following more detailed description and by reference to the accompanying drawings wherein

Fig. 1 is a diagrammatic front elevation of a warm air furnace having combined therewith air conditioning means embodying the present invention;

Fig. 2 is a fragmentary vertical section, to larger scale, showing the casing of the air conditioning apparatus and an air conditioner embodying the present invention therein;

Fig. 3 is a side elevation of the air conditioning unit removed from the casing of the conditioning apparatus;

Fig. 4 is a side elevation of the air conditioning element removed from the holder of Fig. 3;

Fig. 5 is an enlarged side elevation of the frame elements and the conduit of Figs. 3 and 4 with parts broken away;

Fig. 6 is an enlarged section on the line 6—6 of Fig. 3;

Fig. 7 is an enlarged section on the line 7—7 of Fig. 4; and

Fig. 8 is an enlarged section on the line 8—8 of Fig. 4.

The numeral 1 designates a warm air furnace of conventional type having the fire door 2 giving access to a fire box; the ash door 3; and the outer casing 4 within the lower part of which is the cold air inlet chamber 5 (Fig. 1) and in the upper part of which is the plenum or air distributing chamber 6, from which the warm air pipes 7 lead to the several points of use.

As here illustrated, the air conditioning apparatus which is associated with the furnace is arranged outside of the furnace structure, but it is contemplated that all or certain portions, at least, of this air conditioning apparatus may be arranged within the furnace casing if desired, the

2

casing being correspondingly designed to receive it.

As here illustrated, the air conditioning system comprises a casing 8 which may be of sheet metal or the like, having the inlet portion 9 and the exit portion 10, the latter being connected directly to the casing 4 of the warm air furnace and providing communication between the interior of the casing 8 and the distributing chamber 6. As illustrated, a cold air pipe 11 leads from the cold air inlet chamber 5 of the furnace casing to the inlet of the air conditioning system. However, it is not necessary that the inlet 9 be connected with the cold air chamber of the furnace since the inlet 15 9 may be arranged to receive air from any suitable source. Between the inlet 9 and the exit portion 10, the casing is enlarged to provide the conditioning chamber 12. Within this chamber and forming a substantial barrier transversely 15 thereof is a radiator 13, preferably of conventional automobile type, having a multitude of horizontal air passages 14 and a large number of small vertical tubes 15 connecting a chamber 16 in the upper part of the radiator structure 20 with a similar chamber in the lower part of the radiator structure, the tubes and these chambers forming cavities for the reception of liquid which is in effective heat exchange relation to the air passing through the horizontal passages 14.

Within the fire box of the warm air furnace or so located as to be exposed to the heat of the fire in the fire box, or to radiation from the fire box, there is arranged a liquid heating device 17, here illustrated as a simple coil of pipe. However, other types of liquid heating means may be used. The delivery end of this coil 17 or equivalent heating means is connected to a pipe 18, while the inlet of the coil 17 is connected to a pipe 19, these pipes extending out through the casing 4. The pipe 18 is connected to a fitting 20 to one arm of which there is attached a safety valve device 21. To another arm of this fitting there is connected a supply pipe 22 coming from any suitable source of water at supply pressure, and from another arm of the fitting 20 a nipple 23 extends downwardly into the top of the radiator 13.

The pipe 19 leads to a T-fitting 24 from which a nipple 25 extends upwardly to the lower part of the radiator 13. There is thus established a continuous path for liquid to circulate through the heater device 17 and the liquid receiving cavities of the radiator.

Within the exit portion 10 of the conditioning casing, there is arranged a transverse vertical

sheet of foraminous material 26, preferably made of wire mesh fabric or of an open mesh textile material. Just above this screen there is arranged a distributing pipe 27 having drip openings 27a from which water or other liquid may be delivered onto the upper portion of the screen 26 so as to flow down over the screen in a very thin film to be easily absorbed by air passing through the interstices of the screen. A supply pipe 28 brings water or other fluid to the distributing pipe 27, the pipe 28 having one end connected to a T-fitting 29 and its other end connected to the union 28a. The pipe 30 affords a communication between the T-fitting 29 and the cold water supply, this pipe being provided with a valve 30a by which the amount of cold water passing through the pipe 30 to the distributing pipe 27 may be controlled. Another pipe 31 is connected to the T-fitting 29 and to the T-fitting 24 and is designed to receive warm water from the nipple 25 so that when desired warm water may be supplied to the screen 26 instead of cold water. The pipe 31 is provided with a valve 31a which is operative to control the amount of warm water passing through the pipe 31 to the distributing pipe 27.

Immediately below the screen 26 there is provided a collecting trough 32, U-shaped in cross-section, designed to receive any moisture which may drip from the lower edge of the screen. A drain pipe 33 leads from this trough to any desired point. The claims relate to the foraminous material 26, the distributing pipe 27 and other associated parts which will be described in more detail hereafter.

Within the exit portion 10 of the casing there is preferably arranged a series of air guiding louvres 34 which may be adjustable, if desired, or which may be fixed at an angle found experimentally to give the best results in the particular installation. These louvres tend to smooth out eddies in the flowing air and to provide a smoothly flowing stream where the air enters the distributing chamber 6 of the furnace. As illustrated, they are so arranged as to direct the air upwardly where it enters the distributing chamber so that the flow of air into the pipes 7 is facilitated.

While the apparatus may depend upon gravity flow of air for circulation or upon the employment of a fan located at some other point in the heating system, it is preferred to provide a support 35 within the casing 8 and to mount thereon a motor 36, driving a fan 37 so arranged as to draw in air through the inlet 9 and to deliver it in a substantially horizontal stream to flow through the passages 14 of the radiator 13.

A frame assembly for the sheet of foraminous material 26 is provided by a metal tube which is bent to provide side frame members 40 and 41 and a bottom frame member 42. The top frame member 43 of this assembly has its ends secured to the upper ends of the side frame members 40 and 41. One end portion 43a is provided with a passage which is adapted loosely to receive the distributing pipe 27. Its opposite end 43b is provided with a socket which is adapted loosely to receive the closed end of the distributing pipe 27.

The sheet of foraminous material 26 is secured to the frame assembly by wrapping its sides and ends around the frame members 40, 41, 42 and 43 and then securing them by a strand of wire or other suitable material 44 to the main body portion of the sheet, the corners of the sheet being notched at 45a.

Thus a passage having an opening at one end is provided by the bore of end portion 43a, the frame member 43, the socket in the end portion 43b and the loop 26a (Fig. 7) of foraminous material which is formed at the top of the sheet of foraminous material. By manipulation of the union 28a, the pipes 27 and 28 are separated and the distributor pipe 27 may then be withdrawn by sliding it longitudinally of the passage. This permits cleaning of the orifices 27a or replacement of the distributor pipe by a new one.

The frame assembly 40, 41, 42 and 43 is removably supported in a holder frame formed by the trough 32, the holder side frame members 45 and 46 and the holder top frame member 47. The lower ends of the holder side frame members are secured to the trough 32 by soldering, welding or any other appropriate means to form water-tight ends for the trough. The nipple 49 is secured to the member 46 and is detachably secured to the outlet pipe 33 by a union 50. The holder top frame member 47 is detachably secured to the upper ends of the side members 45 and 46, for example, by the resiliency of its side walls.

The trough 32 and holder frame members 45, 46 and 47 are each U-shaped in cross-section and they receive and enclose the frame assembly 40, 41, 42 and 43. By removing the holder top frame member 47, the resultant U-shaped holder frame 45, 32 and 46 may be completely removed from the frame for the foraminous material.

The portion 10 of the casing is provided with a slot 51 which is adapted to receive the holder frame assembly 32, 45, 46 and 47. A channel member 52 (Fig. 2) communicates with the lower end of this slot and another channel member 53 communicates with the upper end thereof. Thus the holder frame assembly with the frame for the foraminous material in place therein may be slid inwardly through the slot to its vertical position wherein the foraminous sheet 26 extends transversely of the portion 10 of the casing and it may be removed by sliding it outwardly through the slot.

45

Operation

In operation the sheet of foraminous material may be utilized either to add moisture to the air or to remove moisture from the air. To remove moisture from the air, the water or other fluid supplied to the distributor pipe 27 is provided with a temperature which is below the temperature of the air which is being circulated through the casing 10. To add moisture to the air, the water or other fluid supplied to the pipe 27 has a temperature which is above the temperature of the air circulated through the conduit 10. When the temperature of the water or other fluid is lower than the air, it causes moisture in the warmer air to condense and to flow down the screen 26 and accumulate in the trough 32 from which it passes outwardly through the pipes 49 and 33 to a drain. When the water supplied to the pipe 27 is the same temperature as or warmer than the air, the air takes up moisture from the film of moisture on the screen 26. The temperature of the water or other fluid supplied to the pipe 27 may be controlled by appropriate adjustment of the valves 30a and 31a, or if desired, by varying the temperature of the water supplied to either the pipe 30 or the pipe 31.

In operation the fan 37 continuously blows a stream of air through the sheet of foraminous material 26 and thence through the conduit 1 to the distributing points. The distributing pipe

27 continuously supplies liquid to the upper portion of the sheet of foraminous material 26 and the liquid flows by gravity downwardly along the foraminous material. Any liquid which is not consumed by the air passing through the foraminous material is collected in the trough 32 and passes outwardly through the pipes 49 and 33 to the drain. The film of water may be utilized not only to control the amount of moisture in the air but it also washes the air and removes dirt and dust from it. The film of water tends to carry this dust and dirt downwardly to the trough 32.

Preferably the valves 30a and 31a are adjusted to provide a very thin film of water on the screen of foraminous material 26. The screen may be cleaned at intervals by increasing the flow of water or other fluid from the pipe 27, thereby washing any accumulations of dust or dirt downwardly into the trough 32.

The unit may be removed from the portion 10 of the casing by releasing the union couplings 28a and 50 and then sliding the holder frame assembly outwardly from the casing through the slot 51. The frame for the foraminous material may be removed from the holder frame assembly by lifting the holder top frame member 27 upwardly away from the side members 45, 46 and then sliding the foraminous material frame member 40, 41, 42, 43 outwardly through the open end of the holder frame assembly. The distributor pipe 27 may then be removed by sliding it outwardly through the passage which is formed at the top of the foraminous material frame assembly. The unit may be re-assembled by re-inserting the distributor pipe 27 in the passage, sliding the foraminous material frame assembly into the U-shaped holder frame assembly, placing the holder frame top member upon the upper ends of the side members 45, 46, sliding the assembly inwardly through the slot 51 and re-coupling the pipes 49 and 27 to the pipes 33 and 28, respectively.

While the apparatus has been illustrated in association with a hot air furnace, it may be associated with any air circulating system without departing from the scope of this invention. For example, the apparatus may be utilized to cool warm air in the summer and in such use, it may be utilized either to add moisture to or remove moisture from the air.

While we have disclosed the use of water, other fluids may be utilized. For example, fluids which remove moisture from the air at room temperature may be substituted for water, if desired.

It will be apparent to persons skilled in the art that we have provided a novel and efficient air conditioning unit which will efficiently wash or clean air circulated therethrough, which may be utilized to add moisture to or remove moisture from the air, which may be readily disassembled for repair and cleaning and which may be readily installed in a common air circulating system.

This application is a continuation-in-part of our copending application Serial No. 620,960, filed October 8, 1945, entitled "Air Heating and Humidifying Apparatus," now Patent No. 2,424,927.

While one desirable embodiment of the invention has been illustrated by way of example, it is to be understood that the invention is broadly inclusive of any and all modifications falling within the scope of the appended claims.

We claim:

1. An air conditioner comprising a substan-

- tially rectangular screen frame assembly having side, top and bottom screen frame members and a sheet of foraminous material substantially bridging the gap between said screen frame members and having its sides and ends secured respectively to said screen frame members, a longitudinal passage formed in said top screen frame member, extending substantially between the side screen frame members adjacent the tops thereof and outwardly transversely of the upper portion of at least one of said side frame members to provide an opening for said passage in one outer side wall of the frame assembly, a conduit detachably mounted in said passage and extending outwardly of the frame assembly through said opening, said conduit being provided with a series of perforations through which a liquid may flow to said sheet of foraminous material, and means for detachably connecting said conduit to a source of liquid, whereby said conduit may be removed from said longitudinal passage by withdrawing it through said opening and without removing the foraminous material from the screen frame members.
2. An air conditioner comprising a substantially rectangular screen frame assembly having side, top and bottom screen frame members and a sheet of foraminous material substantially bridging the gap between said screen frame members and having its sides and ends secured respectively to said screen frame members, a conduit extending substantially between the side screen frame members adjacent to the top of said sheet of foraminous material, said conduit being provided with a series of perforations through which a liquid may flow to said sheet of foraminous material, means for detachably connecting said conduit to a source of liquid, a trough, U-shaped in cross section with its side walls substantially higher than the height of said bottom screen frame member, whereby when the bottom screen frame member is supported on the bottom of the trough a space is provided in said trough above said screen frame member for the accumulation of liquid from the foraminous material, two side holder frame members extending upwardly from said trough, one at each end thereof, said side holder frame members being U-shaped in cross section, the trough and side holder frame members being secured together at their adjacent ends to form a U-shaped holder frame for detachably supporting said rectangular screen frame assembly, and a conduit communicating with the interior of said trough for conducting away liquid which accumulates therein from the foraminous material.
3. In an air conditioner comprising a substantially rectangular screen frame assembly having side, top and bottom screen frame members and a sheet of foraminous material substantially bridging the gap between said screen frame members and having its sides and ends secured respectively to said screen frame members, a conduit extending substantially between the side screen frame members adjacent to the top of said sheet of foraminous material, said conduit being provided with a series of perforations through which a liquid may flow to said sheet of foraminous material, and means for detachably connecting said conduit to a source of liquid, and a holder frame assembly comprising a bottom holder frame member, U-shaped in cross section, for detachably receiving and supporting the bottom screen frame member and forming a trough for the accumulation of liquid from the foramin-

inuous material, and two side holder frame members extending upwardly from said bottom frame member, one at each end thereof, said side holder frame members being U-shaped in cross section for detachably receiving and retaining the respective side screen frame members, whereby the screen frame assembly may be removed upwardly as a unit from the holder frame assembly.
